US00D780070S

(12) **United States Design Patent** (10) **Patent No.:** **US D780,070 S**
Anderson (45) **Date of Patent:** **** Feb. 28, 2017**

(54) **TRAILER JACK**

(71) Applicant: **Cequent Consumer Products, Inc.**,
Solon, OH (US)

(72) Inventor: **Derek Anderson**, Newbury, OH (US)

(73) Assignee: **Cequent Consumer Products, Inc.**,
Solon, OH (US)

(**) Term: **14 Years**

(21) Appl. No.: **29/522,832**

(22) Filed: **Apr. 2, 2015**

Related U.S. Application Data

(63) Continuation of application No. 29/447,444, filed on Mar. 4, 2013, now Pat. No. Des. 727,213.

(51) **LOC (10) Cl.** **12-10**

(52) **U.S. Cl.**

USPC **D12/106**

(57) **CLAIM**

The ornamental design for a trailer jack, as shown and described.

DESCRIPTION

FIG. 1 is a perspective view of a trailer jack showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

In the drawings, the broken lines depict portions of the article that form no part of the claimed design.

1 Claim, 4 Drawing Sheets
